UNITED STATES PATENT OFFICE.

HARLAN LEONARD POTTS, OF POTTSTOWN, PENNSYLVANIA.

FASTENER FOR SHOE-STRINGS, BAGS, &c.

SPECIFICATION forming part of Letters Patent No. 423,808, dated March 18, 1890.

Application filed April 29, 1889. Serial No. 308,953. (No model.)

To all whom it may concern:

Be it known that I, HARLAN LEONARD POTTS, a citizen of the United States, residing at Pottstown, in the county of Montgomery and State

5 of Pennsylvania, have invented a new and useful Improvement in Fasteners for Shoe-Strings, Bags, &c., which improvement is fully set forth in the following specification and accompanying drawings.

10 My invention consists of a fastener for a shoe-string, bag, &c., formed of jaws, which are connected at one end and provided with a tongue and groove, as herein described and claimed, whereby the string may be conveniently applied and removed and when in position firmly held.

Figure 1 represents a perspective view of a fastener for a shoe-string embodying my invention. Fig. 2 represents a side elevation 20 on an enlarged scale. Fig. 3 represents a transverse section thereof. Fig. 4 represents a longitudinal section thereof. Fig. 5 represents a perspective view of a modification.

Similar letters of reference indicate corresponding parts in the several figures.

Referring to the drawings, A designates the fastener, the same being constructed of the jaws B and C, which are connected at one end as integral, leaving the other end open and flaring for the insertion of the string between them. The upper jaw B is made of greater thickness than the lower jaw C, the latter, owing to its being fastened to the shoe, not requiring heavy material therein. The inner 35 face of one of the jaws has a tongue D, and that of the other jaw has a groove E, said tongue projecting toward said groove, so as to provide a "biting" action on the string when the latter is in position.

40 It will be seen that the string is presented to the jaws so as to enter between the same, and is drawn inwardly, riding against the tongue and wall of the groove. The jaw B held at one end is somewhat elastic, so that 45 it yields and allows the string to enter to considerable extent, and then exerts its pressure, so that the string is tightly clamped and thus firmly held, the hold being increased by

the tongue and groove bending or deflecting said string as said tongue and groove lengthen 50 the contact-surfaces of the jaws upon the string.

The jaw C is provided with spurs F, of flexible metal, for fastening the device to a shoe, bag, &c.; or, in lieu thereof, an eyelet G may 55 be formed with or secured to said jaw for evident purposes; but, if desired, the jaw may be secured by stitching, for which purpose openings are made in the jaw C, forms of which are shown in Fig. 5. 60

I am aware that it is not new to form a shoe-string fastener of a single piece of metal bent so as to form a jaw, the main portion or body having a raised portion or tongue coinciding with a depression in the jaw portion, so as to 65 prevent the string from readily slipping out from between the jaw and the body portions; but I am not aware that the construction herein shown and described is old—viz., a fastener formed of solid metal having two jaws 70 integral with each other, one of said jaws being provided with a V-shaped tongue and the other jaw having a groove coinciding with said tongue, the said tongue and groove extending from the intersection of said jaws to 75 the ends thereof, so that the string will be firmly nipped between the tongue and groove of the jaws and held in place.

Having thus described my invention, what I claim as new, and desire to secure by Letters Patent, is—

A fastener for a shoe, consisting of a single piece of solid metal formed in two jaws, one of which is provided with a tongue and the other with a coinciding groove, said tongue 85 and groove extending from the intersection of the jaws to the ends thereof, and the under jaw having secured thereto prongs of flexible metal, whereby said fastener may be attached to a shoe, said parts being combined substantially as described. 90

HARLAN LEONARD POTTS.
